UNITED STATES PATENT OFFICE.

EDMOND J. SAUSE, OF BROOKLYN, ASSIGNOR TO HIMSELF AND MAX SCHMIDT, OF BROOKLYN, E. D., NEW YORK.

BILLIARD-TABLE.

SPECIFICATION forming part of Letters Patent No. 242,054, dated May 24, 1881.

Application filed March 22, 1881. (No model.)

To all whom it may concern:

Be it known that I, EDMOND J. SAUSE, of Brooklyn, Kings county, New York, have invented a new and Improved Billiard-Table, of 5 which the following is a specification.

The object of my invention is to provide a new and improved billiard-table on which a game can be played with two or more balls.

The invention consists in a billiard-table provided with the ordinary cushioned end rails, and with a central cushion attached to a stud projecting from the table.

The invention further consists in a series of corresponding marks on the upper surface of 15 the cushion-rails and on a plate above the central cushion.

In the accompanying drawings, Figure 1 is a plan view of my improved billiard-table; and Fig. 2 is a detail cross-sectional elevation of 20 the central part of the same on the line x x, Fig. 1.

Similar letters of reference indicate corresponding parts.

The billiard-table A is provided with the ordinary cushion-rails B along the edges, and with an annular cushion, C, attached to a beveled block, D, mounted on a pin or stud, E, projecting upward from the center of the table, and provided with an annular flange or projection, F, resting on the table. The pin E is fastened to the table by means of a nut, G, screwed on the lower end of the pin and resting against the under side of the table, and the block D is secured on the pin E by means of 35 a nut, H, screwed on the top of the pin E and resting on a circular or polygonal washer-plate, J, placed on the top of the block D.

The central cushion, C, has been described and is shown as being circular, but may be polygonal, the circular or annular form being preferred, and this cushion can be attached to any suitable projection in the center of the table, or between the cushion-rails.

A white or red screw, K, is fastened in the 45 center of each end rail, and a black screw, L, is arranged at each side of this white screw K, midway between the same and the ends of the rails.

The washer-plate J is provided with marks 50 of corresponding color, M and N, respectively opposite, or nearly opposite, to the screws on

the rails. Any other suitable corresponding marks may be arranged on the rails and on the washer-plate. These marks serve to guide the player in making his calculations in regard to the probable direction in which the balls will run. 55

The billiard-table may be constructed with end pockets, O O, or they may be omitted.

The game is played on this billiard-table as 60 follows: One ball is placed upon the mark P on the table, between the central cushion and the longitudinal end rails, and the other ball must be shot in such a manner that it will strike the first ball resting on the mark P, and 65 must then strike the cushion, or it can strike the cushion first and then the ball. A point is made if one ball and the central cushion are struck, or a point is made if the opponent's ball enters one of the pockets. More than two 70 balls can be used, if desired.

It is evident that shots can be made on my improved billiard-table which are not possible on an ordinary table. If desired, more than one cushion can be arranged on the table, but 75 I prefer to have one only.

Having thus described my invention, I claim as new and desire to secure by Letters Patent—

1. A billiard-table made, substantially as shown and described, with annular cushions 80 on one or more projections of the table, between the ordinary end cushion-rails, as set forth.

2. The combination, with the billiard-table A, of the end cushion-rails, B, and of the central cushion, C, substantially as herein shown 85 and described, and for the purpose set forth.

3. The combination, with the billiard-table A, of the pin E, the block D, the cushion C, and the nuts G and H, substantially as herein shown and described, and for the purpose set 90 forth.

4. The combination, with the billiard-table A, of the end cushion-rails, B, provided with distinguishable marks K and L, of the central cushion, C, and the washer-plate J, provided 95 with distinguishable marks M and N, substantially as herein shown and described, and for the purpose set forth.

EDMOND J. SAUSE.
